UNITED STATES PATENT OFFICE.

MELVIN CLOGSTON, OF TERRE HAUTE, INDIANA, ASSIGNOR OF ONE-HALF TO JOSEPH SOEDERS, OF TERRE HAUTE, INDIANA.

LIFTING DEVICE OR GRAPPLER.

1,344,174.

Specification of Letters Patent. Patented June 22, 1920.

Application filed October 13, 1919. Serial No. 330,337.

To all whom it may concern:

Be it known that I, MELVIN CLOGSTON, a citizen of the United States, and a resident of Terre Haute, in the county of Vigo and 5 State of Indiana, have invented certain new and useful Improvements in Lifting Devices or Grapples, of which the following is a specification.

My present invention relates generally to 10 a lifting device and more particularly to article engaging means thereof, or grapple, my object being the provision of a simple, efficient box grappling means which will readily and effectively engage with boxes 15 and in particular with the strongest points of boxes, crates, cases and the like, and which will at the same time be readily and quickly releasable when pressure is released so as to avoid the necessity of special tools, 20 implements and the like for knocking the grapple free.

A more specific object of my invention is the provision of a grapple in which the engaging elements may be readily detached for 25 either sharpening or for substitution or repair in the case of wear or breakage.

With these objects in view, my invention resides in the details of construction to be hereinafter referred to in connection with 30 the accompanying drawing which latter forms a part of this specification and contains several figures, of which,

Figure 1 is a side view illustrating the practical application of one form of my invention,

Figs. 2 and 3 are respectively a top plan and side view, illustrating a slightly different form.

Referring now to these figures, my invention 40 proposes the use of grappling or lifting arms generally indicated at 10 in Fig. 1, and at 11 in Figs. 2 and 3, each of which form has at its outer end a pair of grappling elements in the form of engaging extensions 12, the inner portions of which are secured rigidly along opposite sides of the lifting or grappling arm as by means of bolts 13. This permits of ready detachment of the grappling elements for sharpening, repair or substitution.

Each of the grappling elements 12 has an outer offset portion 14 as best seen in Fig.

2, provided with an angular extension 15 as seen in Figs. 1 and 3, this extension 15 being disposed at right angles with respect to 55 the body of the element and with respect to the lifting or grappling arm to which it is attached, and terminating in a beveled sharpened angular engaging extremity 16, projecting substantially parallel to the lifting 60 or grappling arm.

Thus by virtue of their oppositely offset portions, the two grappling elements of each grappling arm are designed to span the extreme corner of a rectangular object such as 65 a box, crate or case, so that the engaging extremities 16 will seek their hold near the top of the article at its usually strengthened, cleated corner portion.

The grappling arms 10 of Fig. 1 are designed for use where sufficient engagement can be effected at diagonally opposite corners of an article, the inner portions of these arms 10 being provided with a longitudinal series of openings 17 so as to provide for 75 their adjustable connection by means of a clevis 18, with a hoisting ring 19.

On the other hand, the arms 11 of Figs. 2 and 3 are designed for double use, i. e., two at each side, of an article, so as to engage 80 the four corners, each pair of arms being connected by links 20 with a ring 21, the latter of which in practice are usually connected to the lifting ring 19 of Fig. 1, by adjustable chains.

It is obvious that in the practical application of my invention, it is possible, in view of its particular construction to engage a rectangular article at the corners along the usually present reinforcing cleats and thus 90 at its strongest points, and it is also obvious that the article will be grappled near to its upper surface so that the grappling elements may be readily and easily released.

It is also obvious my invention proposes 95 a grappling device which is applicable to various sizes of articles, is capable of sustaining its load equally balanced and without undue strain on any part and that, beyond the foregoing it is simple, strong and 100 durable.

I claim:

A grappling device for rectangular articles, including grappling arms, each hav-

ing at opposite sides of its outer end the separately attached inner extensions of grappling elements of similar construction disposed in spaced apart relation, each of said grappling elements being provided with an offset intermediate its ends adjacent the end of its grappling arm, forming an angular

outer extension terminating in an angular engaging point disposed approximately parallel to the grappling arm, the inner portions 10 of said grappling arms lapping one another and having lengthwise series of openings, as and for the purpose described.

MELVIN CLOGSTON.
